UNITED STATES PATENT OFFICE.

EUGEN PRESTINARI, OF IRVINGTON, NEW JERSEY, ASSIGNOR TO GEMEX COMPANY, OF NEWARK, NEW JERSEY, A CORPORATION OF NEW JERSEY.

EXTENDIBLE BRACELET LINK.

Application filed November 10, 1927. Serial No. 232,428.

This invention relates to an improved construction of extension device for a bracelet strap; and has for its object to provide such a device formed of two link members hinged together to be folded one upon the other and unfolded to temporarily extend the length of the bracelet, one of the members of the device having side walls with openings therein to receive the ends of the cross bar on one end of the bracelet strap whereby this strap end is detachably and adjustably connected to the extension device.

A further object of the invention is the provision of a plurality of sets of holes in the side walls of one of the link members whereby the ends of the strap cross bar are adapted to enter different pairs of holes providing a step-by-step adjustment to affect the working length of the bracelet.

A still further object of the invention is the forming of the ends of the cross bar on the strap with heads shaped to conform to and enter correspondingly-shaped holes in the side walls of the link member whereby the ends of the bar may enter and be withdrawn from these wall openings only when the strap end is in a position other than working position.

With these and other objects in view, the invention consists of certain novel features of construction, as will be more fully described, and particularly pointed out in the appended claims.

In the accompanying drawings:

Figure 1 is a side elevation illustrating my extension device as applied to a watch bracelet, the device being in folded position.

Figure 2 shows one of the link members as having side walls with a plurality of pairs of openings in the opposite walls.

Figure 3 is a perspective view showing another of the link members which is adapted to be hinged to the first link member to be folded over upon the same.

Figure 4 shows a strap member one end of which is provided with a cross bar having heads or enlargements on its ends to fit into the openings in the side walls of one link member when in a certain position.

Figure 5 shows the two link members as pivotally connected together and folded one upon the other.

Figure 6 is an edge view showing the cross bar on one end of the bracelet strap as protruding through the opening in the side wall

of one of the link members, the other link member being partially folded into closed position.

Figure 7 is a top view showing the two link members as pivoted together and in **60** unfolded or extended position with the opposite ends of the bracelet strap secured to opposite link members, one being permanently secured to the other link member.

Figure 8 is an enlarged view showing one **65** of the heart-shaped openings in the side wall of one of the link members and showing the correspondingly shaped end of the cross bar of the strap end turned into position to be locked in the openings. **70**

Figure 9 shows the end of the bar as swung into position to register with and pass through the correspondingly-shaped opening.

Figure 10 is a top view showing one end **75** of the cross bar as removed from the opening in one wall.

Figure 11 shows the cross bar with one end removed from the opening in the side wall and lifted into position to be withdrawn from the other opening in the opposite side wall. **80**

It is found in the practical use of extension devices for bracelets of advantage to provide means for adjusting the operating **85** length of the bracelet strap to fit arms of different sizes, and to accomplish this in a simple and effective way, I have formed an extension device for such a strap with two sheet metal members hinged together at one **90** end to temporarily extend the length of the strap to pass over the hand of the wearer and to be folded one upon the other to reduce its length to working size, one end of one link member being permanently attached to one end of the strap member while the other end of the strap member is provided with a cross bar adapted to be adjustably connected to the side walls of the other link member whereby this working **95** length may be adjusted to fit the wrist of the different wearers. In order to prevent accidental detachment of this adjustable end from its link member, I have enlarged or formed heads on the ends of the cross bar **100** and so shaped these ends as to register with the correspondingly-shaped openings in the side walls of the link member only when the strap member is not in operating position, but when the strap end is in operating posi-

110

tion the bar is locked against inadvertent removing; and the following is a detailed description of the present embodiment of my invention and showing one means by which these advantageous results may be accomplished.

With reference to the drawings, 10 designates the bracelet strap which is herein shown as being connected to a wrist watch 11. Between the opposite ends 12, 12^a of this strap I have interposed an extension device for the strap by which its length may be temporarily extended sufficiently to be passed over the hand of the wearer without completely disengaging its ends one from the other and to accomplish this I have provided a body link member 13 having side walls 14 with oppositely disposed pairs of holes 22 made in a shape other than round, preferably in heart shape and to this body member I have pivotally connected at 15 another sheet metal plate member 16 adapted to be swung over and folded upon the body member in the positions illustrated in Figures 1 and 5, the extremities of the folding member being turned outwardly forming engaging lips 17 to snap over the ends 18 of the walls of the body member and so detachably secure these two members in folded position.

The free end of this foldable member 16 is permanently attached by a cross pin 19 to the inner end 12^a of the bracelet strap while the opposite end 12 of this bracelet strap is provided with a cross bar 20, the extremities of this latter cross bar being enlarged providing heads 21 herein shown as being of a heart shape to pass through the correspondingly shaped opening 22 in the side walls 14 only when these heads are turned into proper position to register with these holes 22.

This cross bar 20 is, however, fixed either by solder or rivets in set position in the strap end 12 so that in order to pass these heart-shaped heads through the openings 22 in the side walls of the link the strap 12 must be thrown over from its operating position, as illustrated in Figure 8 to its inoperative position, as illustrated in Figure 9, in which latter position the heart-shaped head will register with the correspondingly shaped openings in the flange 14 and may extend laterally therethrough and when this strap end is turned back into its operating position, as illustrated in Figure 8 this head 21 is locked in its opening against inadvertent removal.

By my improved construction, it will be seen that by swinging the end 12 of the

bracelet strap over towards the hinge of the flange member that the heads may be caused to register with and be readily removed from the openings therein and then inserted into any other desired pair of openings for the purpose of adjusting the operating length of the bracelet to fit wrists of different sizes. After adjustment has been made and the strap end is turned back into operating position the link part 16 is then folded over onto the link part 13, and the fingers 17 snapped over the ends of the side walls and the members of the extension device are secured together in operating position.

The device is very simple and practical in construction and is effective in its operation and by its use the operating length of the bracelet may be readily adjusted and securely locked in adjusted position and at the same time the length of the bracelet may be extended temporarily by unfolding the hinge link parts to such an extent as to permit the bracelet to be readily passed over the hand of the wearer.

The foregoing description is directly solely towards the construction illustrated, but I desire it to be understood that I reserve the privilege of resorting to all the mechanical changes to which the device is susceptible, the invention being defined and limited only by the terms of the appended claims.

I claim:

1. In a bracelet strap, a pair of link members hinged together to fold one upon the other, a strap section connected to one member, the other member having opposite side walls each provided with spaced pear-shaped openings, a second strap section, and a cross bar secured to the said second strap section, said cross bar having its opposite ends provided with beads correspondingly formed to fit the said openings.

2. An extension for a bracelet strap having a pair of strap sections, comprising two link members hinged together to fold one upon the other, one of the strap sections being connected to one of the said link members, the other link member having opposite side walls each provided with spaced openings, said openings having a shape other than round, and the other strap section having a cross bar with extending opposite ends shaped to enter the said wall openings when the strap end is in other than working position and to prevent withdrawal therefrom when the strap is in working position.

In testimony whereof I affix my signature.

EUGEN PRESTINARI.
